UNITED STATES PATENT OFFICE

DONALD S. BARROWS, OF ROCHESTER, NEW YORK

RAILWAY TRUCK

Application filed June 14, 1928. Serial No. 285,472.

This invention relates to railway trucks and more particularly to the construction of the side frames, bolster and associated parts for permitting lateral motion of said bolster with respect to said frames, said bolster being in the present instance of the built-up type.

The principal object of my invention, generally considered, is the improvement in car trucks for increasing the flexibility thereof by permitting lateral motion of the bolster of the Huntoon or built-up type, whereby such trucks have the desired flexibility for accommodating themselves to inequalities and curves in the track and for relieving the members thereof from sudden and undue strains.

Another object of my invention is to provide a railway truck utilizing a built-up bolster with castings on the ends thereof adapted to provide rocker seats for lateral motion and interlocking with associated spring caps.

A further object of my invention is to provide railway trucks formed with side frames having bolster openings receiving springs and spring caps, said spring caps being desirably formed with a spring supported portion and upwardly opening pockets receiving the lower ends of rockers, the upper ends of said rockers being received in corresponding downwardly opening pockets in the end castings of built-up bolsters, said end castings being also provided with inner column guide lugs for limiting outward movement thereof with respect to the frames, said rockers being so formed as to provide for centering the bolster.

Other objects and advantages of the invention relating to the particular arrangement and construction of the various parts will become apparent as the description proceeds.

Referring to the drawings illustrating my invention, the scope whereof is defined by the appended claims.

Figure 1 is a partial side elevation, partly in section, of a railway truck, particularly showing the intermediate portions of the compression and tension members of a side frame, the connecting bolster guide columns,

the end of the bolster and the associated connecting parts.

Figure 2 is a transverse sectional view of the frame shown in Figure 1, the associated bolster and spring cap being shown in side elevation.

Figure 3 is a fragmentary transverse sectional view on the line 3—3 of Figure 1, looking in the direction of the arrows.

Figure 4 is a fragmentary horizontal sectional view on the line 4—4 of Figure 1, looking in the direction of the arrows.

Referring to the drawings in detail, like parts being designated by like reference characters, there is shown a portion of a truck comprising a side frame 1, formed with a compression member 2, a tension member 3 and bolster guide columns 4 spacing intermediate portions thereof and spaced to leave a window opening 5 therebetween. In the present embodiment, the side frame illustrated is of the type described and claimed in my Patent #1,652,808 of December 13, 1927, on a car truck, but it is obvious that I do not wish to be limited to the embodiment of this invention in such a type of frame, this showing being preferred but not limiting.

As more fully described in my prior patent, the side frame 1 involves auxiliary tension members 6 which cut across the lower corners of the window or bolster opening 5 and form upwardly extending convolutions which strengthen the frame and serve for interlocking the spring plank 7 with respect thereto, said spring plank being for that purpose provided with corresponding upwardly extending convolutions or corrugations 8. It will be noted that the width of said auxiliary tension members 6 and the corresponding corrugations 8 in the spring plank is less than that of the spring supporting portion of the tension member and preferably corresponds with the diameter of one of the bolster springs 9, as shown in Figure 2.

The auxiliary tension members 6 preferably terminate by merging with the spring supporting portion of the tension member short of the center thereof, whereby a central flat spring supporting area is retained for the central spring unit 10 of the nest of

5 springs. Upon referring to Figure 4 it will be seen that the preferred grouping involves seven spring units arranged as two rows of three spring units disposed on either side of the auxiliary tension members 6 and a single spring unit disposed between said rows and between the central springs of said rows giving a nest of springs substantially H shape in plan, the auxiliary tension members 6 fitting between the ends of the uprights of said H, whereby the horizontal or spring supporting area of the tension member is efficiently utilized for the purpose. Alternative spring arrangements may be employed, if desired, 10 some of which are disclosed in my Patent #1,652,808, previously referred to.

20 Spring plates 11 and 12, the former of which is constructed as disclosed in said patent, may be employed, although I do not wish to be limited to such details. The upper spring plate has to be modified to accommodate the associated spring cap, which will now be described. Resting on the tops of the springs or top spring plate 12, if used, is a 25 spring cap 13, formed with outstanding flanges or lugs 14, which embrace the adjacent portions of the guide columns and hold the cap in proper relation with respect to the frame while permitting up and down movement 30 thereof with variations in the load on the supported bolster 15. In the present embodiment the spring cap is formed as a single casting involving a lower web or wall 16 provided with a depending peripheral flange 17 35 which extends over and embraces the upper ends of the springs 9 and serves to hold them in proper assembled relation.

40 The lower web 16 of the spring cap, which is preferably ribbed for strength on its upper surface, as illustrated most clearly in Figure 4 at 18, is depressed or pocketed downwardly adjacent the bolster guide columns to provide pockets as indicated at 19, which are preferably provided with an aperture 20 near the bottom thereof, as illustrated, to facilitate 45 cleaning, the lower walls 21 of which form bearings for the lower ends of associated rockers 22. The outer walls 23 of said pockets form a connecting web between the flanges 14 and are continued around the front or outer portion of the casting at reduced height as a 50 depending peripheral flange 17, previously referred to, and around the back in the same manner, except that the depth in the present embodiment is slightly greater than at the front.

55 The rockers in the present embodiment are formed roughly triangular in side elevation, the relatively small, pointed or rounded end 24 extending downwardly into the corresponding bearing pockets 19 and adapted to swivel therein in a vertical transverse plane or, if desired, rocking to a limited extent by virtue of having the curvature of its lower end smaller than that of the bearing pocket.

In order to prevent misapplication of the rockers 22 in the bearing pockets 19, one side of the lower end 24 is narrowed or cut away, as indicated at 25 in order to fit between corresponding bosses 26 on the inside of the 70 pocket.

The bolster in the present embodiment is of the built-up type and comprises an angular or channel-shaped compression member 26', a flat tension member 27 and a cast end member 28, said end member being preferably connected to the compression and tension members by common rivets 29. The ends of the tension member 27 preferably fit between the depending flanges 30 of the compression member and are seated on the lower surface of the web 31 thereof, said web preferably being bent upwardly, as indicated at 32 to align with the inclined ends of the tension member 27. The ends of the tension 85 member may be upset, as indicated at 33, to provide shoulders for engaging the ends of the compression member in order to more firmly connect the parts and relieve the rivets 29 of some of the strain. The end castings 28 90 are seated on the ends of the tension member and are provided with downwardly opening pockets 34 for receiving the upper ends of the rockers 22 and interlocking the bolster with respect to the spring cap 13. The 95 pockets 34 in the casting are preferably formed with depending lug portions 35 fitting in corresponding notches 36 in the sides of the rockers 22 for holding the parts in proper relation with respect to each other. 100

In addition to the end casting 28, which is connected to the under side of the compression and tension members 26 and 27, side pieces or castings 37 may be provided, formed with inner bolster guide column engaging 105 lugs 38 and connected to the depending flanges 30 of the bolster compression member 26 by rivets or other connecting means 39. An outer plate 40 may be applied to the ends of the bolster, as by having channels or 110 notches 41 formed at the ends thereof and receiving outstanding lug portions 42 on the side plates or castings 37. Although only one end of the bolster and the associated side frame and parts are illustrated, it will be 115 obvious that the other end of said bolster and the other side frame and parts associated therewith may conform with the drawings.

The rockers 22 are desirably formed of the type illustrated in my patent for railway 120 trucks, No. 1,740,143, dated December 17, 1929, with curved upper sides 43 so designed that the bolster is raised slightly upon outward movement thereof, and maintained at the same elevation upon inward movement 125 thereof. It will be clear that inasmuch as the construction is the same at both ends of the bolster, except that the rockers are in opposite positions, self-centering of said bolster is provided for. The pockets 19 receiv- 130

ing the lower ends of said rockers have walls disposed apart a sufficient distance to allow the desired movement of the rockers for a pre-determined lateral motion of the associated bolster.

5 From the foregoing it will be seen that I have devised a truck in which provision is made for transverse movement of the bolster, which bolster is of the Huntoon or built-up type. Although the rockers only permit lateral motion of the bolster in the present instance, it is obvious that I do not wish to be limited to such a showing, as an intermediate plate may be disposed between the spring cap 10 and rockers for permitting transverse rocking of the bolster in longitudinal vertical planes, as illustrated in Figures 1 to 4, inclusive, of my Patent 1,740,143, previously referred to.

15 Having thus described my invention, I claim:

1. A railway truck having side frames and a bolster connecting said frames, said bolster comprising an angular compression member, 20 a tension member connected thereto and extending therebeneath, and cast end pieces connected adjacent the ends of said compression and tension members with their undersurfaces formed with pockets spaced transversely of said bolster to receive lateral motion permitting devices.

2. A railway truck formed with side frames and a bolster connecting said frames and received at its ends in bolster openings 25 therein, said bolster being formed with a compression member, a tension member, cast end pieces and common rivets extending through said end pieces, compression and tension members, said end pieces being formed with lugs adapted to engage the side frames and downwardly opening pockets spaced longitudinally of the side frames and adapted to receive devices for permitting lateral motion of said bolster.

3. A railway truck having a side frame formed with a bolster opening, springs supported in said bolster opening, a spring cap supported on said springs and interlocked with respect to said frame, and a bolster disposed above said spring cap, said bolster comprising an angular compression member and a flat tension member, the ends of said compression and tension members being riveted together and to end castings, the corresponding end casting being disposed above the spring cap and formed with a downwardly opening pocket, the spring cap immediately below said pocket being formed with an upwardly opening pocket extending from below the tops of and between adjacent springs, and rocker means disposed in said pockets for supporting the bolster and permitting lateral motion thereof.

4. A railway truck having a side frame 30 formed with a compression member, a ten-

sion member, bolster guide columns connecting intermediate portions of said members, springs disposed between said columns, a spring cap formed with pockets, spaced longitudinally of said frame, immediately adjacent and between said columns, rockers in said pockets and a bolster supported on said rockers and adapted to move laterally thereon, said bolster comprising an angular compression member, a flat tension member and 70 end castings formed with downwardly opening pockets receiving the upper ends of said rockers and providing surfaces for rocking engagement therewith.

5. A railway truck having a side frame 80 formed with a compression member, a tension member, bolster guide columns connecting intermediate portions of said members, bolster springs disposed between said columns, a spring cap formed with pockets immediately adjacent and between said columns, rockers in said pockets and supported by said cap below the tops of the springs, and a bolster supported on said rockers and adapted to move laterally thereon, said bolster comprising a compression member, a tension member and an end casting connected together by common rivets, said end casting being formed with downwardly opening pockets overlying the pockets in the spring 90 cap for receiving the rockers for permitting the bolster to move laterally with respect to said frame.

6. In a railway truck, a side frame, a bolster comprising an angular compression member, a flat tension member connected thereto and extending therebeneath, cast end pieces connected adjacent the ends of said compression and tension members with their undersurfaces formed with downwardly opening pockets extended longitudinally of the bolster and presenting downwardly facing flat surfaces, lateral motion devices supported by said frames with their upper ends received in said pockets and supporting the bolster, and depending lugs in said pockets received in notches in said devices for holding the parts in proper relation.

7. In a railway truck, a side frame with a bolster opening, a bolster with an end received in said opening, said bolster being formed with a channel shaped compression member, a flat tension member, cast end pieces and common rivets extending through said end pieces, compression and tension members, 115 said end pieces being formed with lugs adapted to engage the side frames and downwardly opening pockets, and devices supported by said frame for swiveling movement with respect thereto and received in said pockets for permitting lateral motion of said bolster.

8. In a railway truck, a side frame formed with a bolster opening, springs supported in said opening, a spring cap supported on said 120 springs and interlocked with respect to said

frame, and a bolster disposed above said spring cap, said bolster comprising an angular compression member and a flat tension member, the ends of said compression and tension members being riveted together and to end castings, the corresponding end casting being disposed above the spring cap and formed with a downwardly opening pocket, the spring cap immediately below said pocket being formed with an upwardly opening pocket, and means with an upper portion disposed in said bolster pocket in rocking engagement therewith and with a lower portion disposed in said cap pocket in swiveling engagement therewith for supporting the bolster and permitting lateral motion thereof.

9. In a railway truck, a side frame formed with a compression member, a tension member, bolster guide columns connecting intermediate portions of said members, springs disposed between said columns, a spring cap formed with pockets immediately adjacent and between said columns, rockers in said pockets and a bolster supported on said rockers and adapted to move laterally thereon, said bolster comprising an angular compression member, a flat tension member, an end casting formed with downwardly opening pockets receiving the upper ends of said rockers and providing surfaces for rocking engagement therewith, and side members connected to the compression member of the bolster and formed with lugs adapted to limit movement of the bolster with respect to said frame.

10. In a railway truck, a side frame formed with a compression member, a tension member, bolster guide columns connecting intermediate portions of said members, bolster springs disposed between said columns, a spring cap formed with openings immediately adjacent and between said columns, rockers in said pockets, and a bolster supported on said rockers and adapted to move laterally thereon, said bolster comprising a channel shaped compression member, a flat tension member extending between the flanges of the compression member and connected to the web thereof and an end casting connected to said compression and tension members, said end casting having downwardly opening pockets overlying the pockets in the spring cap for receiving the rockers to permit the bolster to move laterally with respect to said frame.

11. In a railway truck, a side frame formed with a compression member, a tension member, bolster guide columns interposed therebetween and spaced to leave a window opening, that portion of the tension member between the bolster guide columns being laterally widened for supporting bolster springs, the junctions between said tension member and bolster guide columns being reinforced by auxiliary diagonal tension portions of less width than the spring supporting portion of

the tension member which cut across the lower corners of the window opening and restrict the horizontal area of the spring supporting portion of the tension member, bolster springs supported on said spring supporting portion on either side of and between said auxiliary tension portions, a spring cap supported on said springs and provided with depressed rocker receiving pockets immediately over the auxiliary tension portions so as not to interfere with the bolster springs, rockers in said pockets, and a bolster formed with upper rocker bearings supported on said rockers for lateral motion with respect to said frame, said bolster comprising a channel shaped compression member, a flat tension member with the ends thereof extending between the depending flanges of the channel member and connected to the web thereof and an end member connected to the corresponding end of said bolster and in which is formed the rocker bearings, and side members on said bolster connected to the flanges of the compression member and formed with lugs adapted to engage the bolster guide columns and limit movement thereof.

12. A built-up bolster comprising a channel shaped compression member with an upper web and depending side flanges, a flat tension member and end castings, said compression and tension members being connected together and to the end castings by common rivets, said end castings being formed with downwardly opening pockets, spaced transversely of said bolster, for receiving lateral motion devices.

13. A built-up bolster comprising a channel shaped compression member, a flat tension member with the ends thereof extended between the flanges of the compression member and connected to the web thereof, the ends of said web being upwardly bent to align with the ends of the tension member, an end casting connected at the end of said bolster and formed with downwardly opening pockets adapted to receive lateral motion devices, and side members connected to the outer surfaces of said depending flanges of the compression member and formed with outstanding lugs for limiting lateral motion of said bolster.

In testimony whereof I affix my signature.
DONALD S. BARROWS.
